BLADE HOUSING FOR LAWN MOWER

Roy Paul Hess, Cleveland Heights, Ohio, assignor to
MTD Products Inc., Cleveland, Ohio, a corporation
of Ohio

Filed June 13, 1969, Ser. No. 17,699

Term of patent 14 years

Int. Cl. D8—01

U.S. CL. D40—1

Fig. 1

Fig. 2

Fig. 3

Fig. 4

Fig. 5

Fig. 6

Fig. 7

FIG. 1 is a perspective view of a blade housing embodying my design, shown on a smaller scale than that of the remaining figures;

FIG. 2 is a top plan view of the same;

FIG. 3 is one end view of the same;

FIG. 4 is a bottom plan view of the same;

FIG. 5 is one side view of the same;

FIG. 6 is an opposite side view of the same; and

FIG. 7 is an end view opposite of that of FIG. 3.

I claim:

The ornamental design for a blade housing for lawn mower, substantially as shown.
